CONTAINER

Herbert L. Carpenter, Brooklyn, N. Y., assignor
to Carpenter Container Corporation, New York,
N. Y., a corporation of Delaware

Application February 8, 1933, Serial No. 655,851

9 Claims. (Cl. 229—5.5)

This invention relates to containers and particularly to fiber containers, the object being to provide an improved simplified container which presents a maximum strength with a minimum amount of material.

Another object of the invention is to provide a container formed wholly of fiber and constructed to present an exceptionally strong structure at both ends.

10 A further object of the invention is to provide an all fiber container having a minimum number of elements, yet presenting a strong type of construction at a minimum cost.

Another object is the provision of an improved 15 container formed principally of fiber and constructed to be appreciably reinforced at each end and at the same time present a light structure which is proof against leakage of the contents, whether wet or dry, as well as proof against 20 the loss or admission of moisture.

An additional object is to provide an improved container wherein the parts are formed principally of fiber, and also wherein the closure may be removed and again re-applied and re-sealed 25 without injuring either the container or the closure.

An additional object is to provide a form of 30 closure for containers of formed and molded fiber construction with superimposed air-proof or moisture-proof material to make the fiber heading and closure proof against the passage of gases, oils or moisture through the closure of the container, combined with superimposed impervious materials between the laminations of the 35 wall of containers, thereby providing a strong and light container, highly resistant to the entry or escape from the container of moisture, gases or liquid materials.

In the accompanying drawings—

40 Figure 1 is a side view of a complete container embodying the invention;

Figure 2 is an enlarged fragmentary sectional view through Figure 1 on the line 2—2;

45 Figure 3 is a view similar to Figure 1 but showing a modified form of the invention, the modification consisting of presenting a collapsible square container;

Figure 3a is an end view of the body portion of 50 the container shown in Figure 3, the same being shown in a collapsed position;

Figure 4 is a view similar to Figure 2 but showing the complete head, the structure being a modified form to that shown in Figure 2;

55 Figure 5 is a view similar to the upper part of Figure 2 but showing a modified form thereof;

Figure 6 is a view somewhat similar to the upper part of Figure 2 but illustrating a modified form thereof;

Figure 7 is a view similar to Figure 6 but showing a modified structure;

Figure 8 is a view similar to Figure 2 except the chime is deeper with the outside flange substantially even with the bottom of the chime;

Figure 9 is a view similar to Figure 8 but with the flange bent over to secure a better sealing 10 and reinforcing action;

Figure 10 is a view similar to Figure 8 but showing a modified arrangement of reinforcement;

Figure 11 is a view similar to the upper part of 15 Figure 2 but showing a modified form thereof wherein metal straps are used;

Figure 12 is a view similar to Figure 11 but showing a modified arrangement which includes metal clips;

Figure 13 is a view similar to Figure 12 but illustrating a modified structure including a row 20 of stitches;

Figure 14 is a view similar to Figure 3 except that it is on the bottom and showing another 25 way of fastening the end to the body;

Figure 15 is a view similar to Figure 14 but eliminating the stitching and substituting a metal clamping band;

Figure 16 is a view of an end wherein reinforcing beads are provided.

Referring to the accompanying drawings, Figure 1 shows a container embodying the invention where all the parts are fiber except the adhesive and the fabric strips 1 and 2. 35 These strips are held in place by suitable adhesive and connect the head 3 and the bottom 4 respectively to the body 5. The body 5 may be a single piece of molded fiber, or may be laminated as shown in Figure 2. Also, if desired, 40 under some circumstances, the body 5 may be made of some other material and yet the head 3 and bottom 4 and other parts function as shown in the drawings and hereinafter fully described.

45 The respective ends of the container are identical, that is, head 3 and bottom 4 are made identical and are held in place in an identical manner, if desired. However, ordinarily a layer of glue or other adhesive 6 permanently connects the bottom 4 to the body 5, while the head 3 is held in place by friction and by the textile fabric 1 and the adhesive coating therewith. If desired, however, adhesive could be used for assisting and holding the head or closure 3 in 50 55

place. As the head or closure 3 and the bottom 4 are identical, the description of one will apply to both.

When it is desired to form a head with three 5 layers of fiber and a layer of water-and-air-proof material, three fiber discs are secured and one disc of moisture-proof-and-air-proof material is secured. This may be "Cellophane" or any other desired material without departing 10 from the invention. As shown in Figure 2, the inner layer 7 of the fiber is smaller than the two outer layers 8 and 9. The layer of "Cellophane" or other water-proof material 10 is of the same size as the layer 7. When the parts have been 15 formed into a closure, as shown in Figure 2, the smaller disc 7 and the "Cellophane" 10 will extend across the main or outer part of the closure and upwardly and over the end of the body 5 of the container but not downwardly on the outside. 20 As shown in Figure 2, the upper surface of the body 15 of the closure 3 will be concave. However, in some of the closures, the upper surface of the section is straight. In Figure 2, the body 15 has been shown as concave. This is desirable 25 in that it helps to distribute the strain from the body of the container in case the container when filled is dropped and strikes on either end. The strain will be distributed radially to the body 5 and unless the strain is sufficiently great to rupture the parts, it will be taken up and sustained 30 by the body 5. It is possible that under these circumstances the body portion 15 may bulge outwardly, but as soon as the pressure is relieved it will automatically go back to its normal 35 position as shown in Figure 2, thus maintaining a proper sealed condition.

As shown in Figures 1 and 2, the container is formed with a body of laminated material and one of the layers, namely, layer 19, is formed of 40 "Cellophane" or some other moisture-proof and air-proof material. By this construction and arrangement the inner wall 14 of the closure 3 braces the end of the body 5 in one direction, while the outer wall or flange 17 braces or holds 45 it in the opposite direction. In order to permanently hold the closure in place, a textile fabric strip 1 is placed in position, as shown in Figures 1 and 2, the same having been applied with some sort of adhesive as, for instance, glue. 50 When providing the strip of fabric 1, the same may be cut on the bias and, consequently, comprises a bias strip which when applied has the ability of adjusting itself to hug or come in intimate contact with surfaces having different diameters. For instance, the section or portion 1' 55 fits smoothly and tightly the outer wall 17 and the portion or section 1" fits the body 5 which is of less diameter. In this way a snug fit of the strip of fabric is secured throughout without 60 any tendency of puckering. If desired a strip of stretchable material not cut on the bias may be used and good results secured.

When it is desired to open the container and consequently remove the closure 3, a knife may 65 be run along the part 20, and usually there is a slight space beneath this portion so that the knife may readily cut the fabric without injuring any of the other parts. The closure 3 may then be pulled off to secure access to the contents. If 70 desired, the closure may be again placed in position and another strip of fabric 1 applied, whereupon the container is reclosed and re-sealed.

It will be noted that in the form of the invention shown in Figures 1 and 2, all parts of the 75 container including the closure and the bottom,

are made of fiber except the adhesive used, the fabric strips 1 and 2 and the "Cellophane" 10 and 19. It will thus be seen that there is no metal used in this structure and the container is what may be termed an all fiber container. 5

In Figures 3 and 3a a modified form of the invention is shown wherein the body 21 and also the ends are formed square. The ends are constructed identical with those shown in Figure 2 except that they are square. When these ends 10 have been removed, or before they are applied, the body 21 may be collapsed, as shown in Figure 3a, so that a number of the containers may be shipped in this collapsed form and set up at their destination, thus economizing on the space 15 used during their shipment. It is to be understood that the same combination of a collapsible shell or body may be used with cylindrical or other shaped containers by the proper creasing or forming of the shell so that it may be collapsed and 20 when opened form the desired shape. Where the container is cylindrical or some other shape, the top and bottom closures or end members will be of that shape and will permanently hold the body in that shape when applied. 25

Figure 4 shows a modified form of the invention which is in most particulars identical with that shown in Figure 2, but modified to provide a bunghole or opening, the same being provided with a metal, fiber, rubber, or other sleeve 22 held 30 in place by friction and by adhesive. The interior of the sleeve 22 is threaded for receiving a threaded plug 23. In this form of the invention, the "Cellophane" or other moisture-proof member 24 is not arranged between the layers of the body 35 portion 15 but on the bottom thereof, so that when a water-proofing coating 25, as, for instance, asphalt is poured in through the opening formed by sleeve 22, said liquid may be distributed over the bottom and side walls of the container, and 40 also, over the closure 3. As illustrated, the coating adheres to the "Cellophane" 24, which "Cellophane" is unattached to the head 3 except by the sleeve 22. The coating 25 connects with the "Cellophane" 24 and forms an annular thickened 45 portion 26 merging into a side wall covering 27. This structure is desirable in that it makes the container absolutely moisture-proof, and in addition, the end coating 25 is not attached directly to the closure 3 so that if the container should 50 be dropped, and the closure 3 should become injured and somewhat loose, it would not break the seal because the coating 25 and the "Cellophane" 24 would merely move away from the closure 3 without breaking any part. If desired, 55 a similar coating could be provided for the structure shown in Figure 2 except for the closure 3.

In Figure 5 a further modified form of the invention is shown which is similar to Figure 2 except in two particulars, one being that the textile 60 fabric retaining strip 28 extends over the top and down into the chime of the closure 3, so that the inner wall or section 29 may be secured by adhesive to the wall 14. The other point of difference is the provision of extra layers 30 of 65 fiber in the body portion 15 but not in the walls 14 and 17. This adds additional reinforcement against collapsing of the container.

Figure 6 discloses a modified structure to those heretofore described but is formed to secure substantially the same result in bracing and sealing action, but in this form of the invention, the closure 3 is formed with two layers, as, for instance, layers 31 and 32, which extend straight 70 across from one side of the container to the other 75

and then downwardly to form the outside flange or wall 17'. This outside wall or flange is secured by the fabric strip 4, as illustrated in Figure 2. However, the inside part is constructed differently from that shown in Figure 2, in that the "Cellophane" or other moisture-proof sheet 33 extends flatwise across the container and immediately below the layer 32, and below the "Cellophane" 33 is another layer of fabric 34 which rests on top 10 of the body 5' of the container. This body may be identical with that shown in Figure 2 or may be made thinner or thicker as desired. In order to provide the inside bracing desired, layers of fiber 35 and 36 are provided, the same being bent 15 down at the periphery for forming a depending flange 37 fitting tightly against the inner surface of the body 5'. In this way there is an inside and an outside brace or holding structure acting to resist inward strain and outward strain in a 20 similar manner to that shown in Figure 2 but with a different structure. After the parts have been formed in suitable dies, they are assembled and held together by adhesive, the adhesive between the layers 31 and 32 being preferably placed 25 on the fiber before the fiber disks are bent and the same is true in respect to the fiber disks 35 and 36.

In Figure 7 another form of the invention is shown wherein a closure is provided having a 30 top portion 38 formed of two sheets of fiber bent to provide a depending flange or outer wall 17''. A single layer 39 is secured to these two layers by adhesive and extends over the top of the body 5'' but not over the outside surface thereof. Below the fiber strip 39 are a plurality of disks 40, the disks being held together by adhesive, and beneath the lowermost, there is arranged a sheet 41 of "Cellophane" or other moisture-proof material which extends from one side to the other 40 of the container upwardly along the walls of the container and then over the top edge thereof, whereby the parts are sealed against the entrance or loss of moisture and at the same time is provided inside and outside bracing members 45 to resist expansion or compression in a similar manner to the way the closure 3 resists expansion or contraction, though by a different construction.

Figures 8 and 9 show a further modified form of the invention wherein the parts are constructed identical with that shown in Figure 2 except that the chime is of greater depth so that the upstanding rim 42 may be bent over as shown in Figure 9, thus forming an interlocked reinforcing and sealing structure 43.

In Figure 10 the same structure as shown in Figure 8 is disclosed but instead of being turned over, as shown in Figure 8, the parts are pressed so as to be deformed inwardly along a central line 44, thus preventing providing an additional contact seal and a reinforcing structure.

In the form shown in Figures 9 and 10, the closure when completed acts as a locked structure and must be destroyed to a greater or less extent in order to secure access to the interior of the container.

In Figure 11 a fragmentary view is shown wherein the same is similar to the upper part of Figure 2 except that instead of using the fabric strip 4, one or more metal strips 45 are used. The strip as shown in Figure 11 is provided with a number of spurs 46 at the lower end adapted to be pressed into the body 5 while the upper part fits over the outer wall 17, extends across the 75 top of the rim 42' and then downwardly present-

ing a hook-shaped extension 47 having spurs 48 pressed into the material for locking the metal strips in place and for locking the closure against accidental removal. When it is desired to remove the closure, member 47 is pulled outwardly and 5 swung over toward the left as shown in Figure 11, until the closure is free, whereupon it may be pulled off the body 5.

In Figure 12 a further form is shown which is similar to Figure 11 but instead of using a metal strip a number of clips 49 are provided, each clip having a pair of spurs 50 adapted to be forced into the ring 42'', thus locking the closure against accidental removal.

An additional modified form is shown in Figure 13 wherein the structure is the same as in the upper part of Figure 2, and also the same as shown in Figures 11 and 12 except that a row of stitching 51 extends horizontally through the ring 42''. This provides an effective lock for the closure so that the same cannot be removed without destruction or without removing the stitching.

Figure 16 shows a top plan view of a slightly modified form of cover wherein the straddling 25 member of the structures shown in the other forms may be used, but various radiating reinforcing ribs have been provided so as to stiffen the center of the cover.

In all forms of the invention no metal is used 30 except in the forms illustrated in Figures 11 and 12, and the metal used in these figures is merely to lock the closure in place and is not essential to the proper sealing and reinforcing of the container.

In Fig. 14 will be seen a structure similar to that shown in Fig. 8 except that it is used at the bottom of the container and is provided with a line of stitching extending through the container and the thin outer wall of the U-shaped straddling member.

In all forms of the invention except that shown in Figures 6 and 7 there is provided a chime in each end of the container which keeps the material in the container away from the floor upon 45 which the container may rest, and this structure presents also great flexibility as well as great strength so that severe internal or external shocks are cushioned, and thereby the material in the container is protected and also the body portion 50 of the container is protected against fracture by reason of the reinforcing functioning of the ends. In any form of the invention it is intended that the chimes at either end of the container may be 55 coated with cellulose or other hardening material or covered with a thin form of metal in order to secure these chimes from wear and to add strength thereto.

I claim:—

1. A fiber container including a fiber body having a closure, said closure being provided with a body portion fitting within the body portion of the container, and an annular outer portion U-shaped in cross-section straddling the end of body portion of the container, said closure being provided with a plurality of layers of fiber material, certain of which form the annular member U-shaped in cross-section, and one other of which extends only from one side to the other of the container body, then parallel with the 70 walls of the container body, and finally to a point across the top of the container so as to brace the container against inward tension.

2. In a closure for containers, a plurality of sheets of fiber and adhesive for securing said 75

- sheets together, said sheets being formed to present a central disk-shaped body merging into an upstanding wall, said upstanding wall merging into a horizontal wall arranged in a plane parallel 5 to said body and merging into a downwardly extending outer wall positioned parallel to the first-mentioned wall, said downwardly extending outer wall having a less number of sheets than said upstanding wall.
10. 3. A fiber closure for a container including three sheets of fiber and adhesive for securing said sheets together, said three sheets being formed to present a circular central body portion, an upstanding annular wall at the outer edge of said body portion, a horizontal member extending from the upper edge of said upstanding wall, said horizontal member being parallel with the top of said body, and a depending outer wall extending from said horizontal member, said depending member being parallel to the first-mentioned wall, said depending wall consisting of 15 two of said sheets of fiber.
15. 4. A container comprising a fiber body formed from a plurality of fiber sheets and a sheet impervious to moisture and arranged between certain of said fiber sheets and a pair of end members, each of said end members consisting of a plurality of sheets of fiber and a sheet of material impervious to moisture arranged between 20 certain of said fiber sheets and of less diameter than the outermost sheet of fiber, each of said end members having the peripheral part formed with a U-shaped structure for receiving the ends of said body, said sheet of material impervious to 25 moisture extending across the end member and one side and the top of the U-shaped structure while the outermost sheet of fiber forms part of 30 three sides of the U-shaped structure.
35. 5. A fiber closure for a container including a plurality of sheets of fiber of varied sizes, an adhesive for securing said sheets together, said closure being formed to provide a U-shaped member having an outside annular flange to fit over a container body, producing a fiber closure 40 of uniform strength and thickness across the center portion of the closure and a U-shaped member of varied strength.
45. 6. A fiber closure for a container including a plurality of sheets of fiber, a sheet of moisture-proof material arranged between certain of said sheets of fiber, and adhesive for securing all of said sheets together, all of said sheets being formed to present a body portion and an upstanding annular wall at the outer edge of said body portion, and a horizontal member extend-

ing from the upper edge of said upstanding wall, and a depending outer wall extending from said horizontal member, said depending member being parallel to the first-mentioned wall and consisting of a less number of sheets of fiber than 5 said upstanding wall.

7. A container including a tubular body, a pair of fiber ends, each end being formed with a disc-like central portion fitting within and engaging the side wall of said body, and a portion at the 10 perimeter of said disc presenting an annular U-shaped structure of a size to fit over the end wall of the body, said disc being of a certain thickness and strength, and the U-shaped structure being of varied thickness and strength with 15 the thinnest part positioned exterior of the body of said container, and a strip of textile fabric overlapping part of said U-shaped structure and part of said body for securing said U-shaped structure to the body, said strip of fabric being 20 stretchable so that the respective portions thereof may conform to the respective sizes of the body and U-shaped structure, the thinness of the wall of the outer part of said U-shaped structure resulting in said strip being distorted to a mini- 25 mum extent when applied.

8. A fiber closure for a container, including a central portion of a given strength and thickness adapted to be fitted within and brace the walls of the container against inward movement, and a 30 substantially U-shaped structure of less strength and thickness positioned at the perimeter of said central portion, said U-shaped structure being adapted to straddle the walls of the container to prevent spreading thereof.

9. A fiber closure for a container, including a plurality of sheets of fiber of various sizes, and adhesive for securing said sheets together, and a moisture-proof layer arranged between certain 40 of said sheets of fiber, all of said sheets extending from one side of the container to the other and forming a closure of uniform strength and thickness across the central portion thereof at the periphery, a certain number of said sheets extending across the walls of the container and others extending across the walls of the container and then downwardly over the outer surface of the container a short distance so as to present a U-shaped member of varied thickness and strength at the perimeter of the central portion, 50 said central portion acting to brace the container against inward movement and said U-shaped member acting to retain the walls of the container against outward movement.

HERBERT L. CARPENTER. 55
